(57) **CLAIM**

The ornamental design for a stackable plant support box, as shown and described.

DESCRIPTION

FIG. 1 is a front, top, and right perspective view of a stackable plant support box showing my new design; FIG. 2 is a rear, bottom, and left perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.
The broken lines shown in the drawings represent portions of the stackable plant support box that form no part of the claimed design.

1 Claim, 8 Drawing Sheets(56)
